Attorney

UNITED STATES PATENT OFFICE.

GEORGE B. LUMMER, OF QUINCY, ILLINOIS.

RAIL-JOINT.

1,153,397.

Specification of Letters Patent. Patented Sept. 14, 1915.

Application filed July 3, 1915. Serial No. 37,910.

To all whom it may concern:

Be it known that I, GEORGE B. LUMMER, a citizen of the United States, residing at the city of Quincy, in the county of Adams 5 and State of Illinois, have invented certain new and useful Improvements in Rail-Joints, of which the following is a specification, reference being had to the accompanying drawings.

10 This invention relates to certain improvements in rail joints and has relation more particularly to a joint of this general character employing threadless bolts; and it is an object of the invention to provide a novel 15 and improved rail joint which may be assembled with convenience and facility and which is effectively maintained in said assemblage.

The invention consists in the details of 20 construction and in the combination and arrangement of the several parts of my improved rail joint whereby certain important advantages are attained and the device is rendered simpler, less expensive and otherwise 25 more convenient and advantageous for use, all as will be hereinafter more fully set forth.

The novel features of the invention will 30 be carefully defined in the appended claims. In order that my invention may be the better understood, I will now proceed to describe the same with reference to the accompanying drawings, wherein—

Figure 1 is a view in top plan, with a part 35 broken away, of a rail joint constructed in accordance with an embodiment of my invention; Fig. 2 is a view in side elevation of my improved joint as herein embodied, with a portion broken away and one of the 40 keys indicated in section; and Fig. 3 is a transverse sectional view taken through the joint as herein disclosed.

As disclosed in the accompanying drawings, 1—1 denote the meeting ends of rails, 45 each of which having produced in the web 2 thereof the longitudinally disposed slot 3 having in communication therewith at substantially its longitudinal center the opening 4, the connecting throat 5 being of a 50 width less than the diameter of the opening. It is also preferred that the opening 4 be positioned above the slot 3.

The meeting ends 1 of the rails are adapted 55 to rest upon the chair 6, the sides of which being provided with the perforate extension 7 to afford a convenient means whereby said

chair may be effectively anchored in applied position. The chair has integrally produced therewith the plates 8 adapted to overlie the base flanges 9 and the webs 2 of 60 the meeting ends 1 of the rails and the web portions 10 of the plates 8 are provided with the aligned key-hole slots 11 with which the openings 4 of the webs 2 are adapted to be brought into register so that the keys 12 65 may be disposed through the webs 2 and 10 and be arranged within the slots 3 to maintain the meeting ends 1 of the rails against displacement.

The opposite extremities of each of the 70 keys 12 are provided with the heads 14 of a formation substantially identical to the formation of the key-hole slots 11, one of said heads being freely insertible through the slots while the second head is of such a 75 size as to be incapable of passing through the openings.

It is thought that the manner of assembling or disconnecting the meeting ends 1 of the rails is clearly apparent from the foregoing description and the disclosure in the accompanying drawings without the necessity of a detailed description of the operation. I also find it of advantage to reinforce the web portions 10 of the plates 8 80 by the webs 15, with a web disposed inwardly of each of the openings 11 and in close proximity thereto, and the webs of a single plate are disposed in converging planes. It is also to be noted that the intermediate portions 16 of the keys 12 are of 85 such a diameter as to readily pass through the connecting throats 5.

From the foregoing description, it is thought to be obvious that a rail joint constructed in accordance with my invention is of an extremely simple and comparatively inexpensive nature and is particularly well adapted for use by reason of the convenience and facility with which it may be assembled, 100 and it will also be obvious that my invention is susceptible of some change and modification without material departure from the principles and spirit thereof and for this reason I do not wish to be understood 105 as limiting myself to the precise arrangement and formation of the several parts herein shown in carrying out my invention in practice.

I claim:

1. A rail joint comprising, in combination, the meeting ends of rails, the web por-

tions of which being provided with longitudinally disposed slots, openings at one side of the slots and in communication therewith, a chair provided with plates engageable with the webs of the rails, said plates being provided with key-hole slots adapted to register with the openings in the webs, and keys insertible through the slots of the plates and the openings of the webs when in register, 10 the extremities of the keys being provided with heads of a formation substantially identical to the formation of the key-hole slots.

2. A rail joint comprising, in combination, 15 the meeting ends of rails, the web portions of which being provided with longitudinally disposed slots, openings at one side of the slots and in communication therewith, a chair provided with plates engageable with 20 the webs of the rails, said plates being provided with key-hole slots adapted to register with the openings in the webs, and keys insertible through the slots of the plates and the openings of the webs when in register, 25 the extremities of the keys being provided with heads of a formation substantially identical to the formation of the key-hole slots, a head of each of the keys being of a

size in excess of the size of the button-hole slots of the plates.

3. A rail joint comprising, in combination, 30 the meeting ends of rails, the web portions of which being provided with longitudinally disposed slots, openings at one side of the slots and in communication therewith, a 35 chair provided with plates engageable with the webs of the rails, said plates being provided with key-hole slots adapted to register with the openings in the webs, and keys insertible through the slots of the plates and 40 the openings of the webs when in register, the extremities of the keys being provided with heads of a formation substantially identical to the formation of the key-hole slots, the connecting throat between each of 45 the slots of the web and the adjacent opening being of a width less than the diameter of the opening, the intermediate portion of a coacting key being of a diameter less than the width of the throat.

50 In testimony whereof I hereunto affix my signature in the presence of two witnesses.

GEORGE B. LUMMER.
